(57) **CLAIM**

The ornamental design for a magnifier head, as shown and described.

DESCRIPTION

FIG. 1 is a front, top, and right perspective view of a magnifier head, showing my new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a right side elevation view thereof; and,

FIG. 7 is a left side elevation view thereof.

The broken lines in the drawings depict portions of the magnifier head that form no part of the claimed design.
